SWITCH CONTROL SYSTEM

Clarence W. Dalzell, Belleville, N. J., assignor to
The Union Switch & Signal Company, Swiss-
vale, Pa., a corporation of Pennsylvania.

Application August 12, 1939, Serial No. 289,893

10 Claims. (Cl. 246—242)

My invention relates to switch control systems for railway track switches, and has particular reference to improved systems of the class in which a selector conditions a railway track switch for operation by either remotely controlled power operating means or by local manual operating means.

In switch control systems of the above class, a selector is provided for a switch operating mechanism and when set in a normal position permits operation of the associated switch by power operating means to a position of correspondence with a polarized switch control relay which is controlled by a control lever located in a remote control office, and which selector when set in a reverse position prohibits operation by power operating means and permits manual operation of the switch by means of a hand lever provided for the switch operating mechanism.

In connection with such dual control switch operating mechanisms, it is desirable to prevent automatic restoration of the switch by the power operating means to its position of correspondence with the switch control relay after the switch has been locally operated and the selector restored to its normal position. Thus, in the event that the switch has been manually operated to a position out of correspondence with the switch control relay, the restoration of the selector to its normal position will not cause the power operating means to automatically restore the switch to the position corresponding with the relay, with the result that movement of the switch under the wheels of a train is prevented in the event the switch is occupied when the selector is restored to its normal position.

Accordingly, an object of my present invention is to provide an improved system of the class described and incorporating means to insure against automatic restoration of the switch upon operation of the selector to its normal position after the switch has been manually operated to a position out of correspondence with the switch control relay.

A further object is to provide an improved system of the class described and incorporating means effective when the switch has been manually operated, to establish remote control of the switch upon operation of a remote switch control lever.

An additional object is to provide an improved system of the class described and incorporating means providing control of a switch from a remote point, and which requires the provision of

but two line wires from such remote point to the location of the switch.

A still further object is the provision of an improved system of the class described and incorporating means providing control of a switch from a remote point through the provision of normally deenergized control line wires.

Another object is to provide an improved system of the class described and incorporating means effective when the switch has been manually operated, to prevent remote control of the switch until the remote control lever is moved to a position out of correspondence with the switch control relay.

A further object is to provide an improved system of the class described requiring a minimum of apparatus for effecting the above and other important objects.

An additional object is to provide an improved system of the class described and employing circuit means controlled by the remote control lever for establishing remote control of a power operating means, and which incorporates a circuit controlling contact operated to an open position when the selector is moved to condition the switch for manual operation, and which contact is restored to its normal closed position only after the selector is restored to its normal position and the remote control lever is moved to a position out of correspondence with the switch control relay.

Another object is to provide an improved switch control system for railway track switches.

Other objects and advantages of my invention will be apparent from the following description taken in connection with the accompanying drawings.

I shall describe two forms of apparatus embodying my invention, and shall then point out the novel features thereof in claims.

In the accompanying drawings, Fig. 1 is a diagrammatic view of one form of an improved switch control system embodying my invention. Fig. 2 is a diagrammatic view showing a modified form of the system shown in Fig. 1 and also embodying my invention.

Similar reference characters refer to similar parts in each of the two views.

Referring first to Fig. 1, the reference character S designates a railway track switch which is operated between a normal and a reverse position by means of a dual-control switch mechanism SM.

Switch mechanism SM, as shown, is provided with a selector SL which operates a link 4.

55

When selector SL is in its normal position, as shown in the drawing, link 4 conditions the switch for operation by power switch operating means, designated by the reference character 5 M, and when the selector is in its reverse position, link 4 conditions the switch to operation by manual operating means, here shown as a hand lever H.

Selector SL also controls a member 5 which rotates about a pivot 6 between a normal position as shown and a reverse position. Member 5 is adapted to engage a contact controlling member 7, pivoted about 6, to move the latter member from its normal position as shown into a reverse position. Member 7 in its reverse position engages a contact member 8 to move member 8 out of engagement with a contact member 9 and thereby open a normally closed circuit controlling contact 8-9 formed by the two contact 10 members. Contact controlling member 7 is biased by any suitable means, such, for example, as a toggle 10, into its last operated position, so that once operated by selector SL to its reverse position, selector SL may be restored to its normal position but member 7 is retained in its reverse position by virtue of the action of toggle 10, thereby holding contact member 8 out of engagement with contact member 9 until such time as member 7 is actuated against its bias into its normal position. Contact members 8 and 9 are biased into mutual engagement with the result that when member 7 is restored to its normal position, circuit controlling contact 8-9 also is restored to its normally closed position by virtue of 15 the bias of members 8 and 9.

Member 7 also is controlled by a reset magnet RM having an armature 11 which at times engages contact controlling member 7, the arrangement being such that when contact controlling member 7 is in its reverse position and armature 11 is in its released position, the energization of magnet RM and consequent operation of its armature 11 to its attracted position operates member 7 against its bias into its normal position, thereby permitting contact 8-9 to become closed. Preferably, the forces exerted by selector SL and the armature of magnet RM are selected and proportioned in such manner that selector SL, when operated into its reverse position to force contact 20 controlling member 7 into its reverse position, exerts a force upon member 7 which exceeds the force exerted upon member 7 by armature 11. Selector SL in its reverse position accordingly holds contact controlling member 7 in its reverse 25 position against the energization of magnet RM, and prevents armature 11 of magnet RM from moving to its attracted position in the event that magnet RM is energized during the interval that selector SL is in its reverse position.

Magnet RM also is provided with a normally open contact 12-12a which becomes closed only when the associated armature 11 is operated to its attracted position. It can be seen that during the interval selector SL is in its reverse position, contact 12-12a of magnet RM cannot be closed if magnet RM is energized, since the associated armature 11 of the magnet cannot be operated to its full attracted position, due to the fact that contact controlling member 7 (which is held in its reverse position by selector SL) engages armature 11 and prevents movement of the armature to its full attracted position.

The power switch operating means of mechanism SM, hereinbefore referred to, is illustrated 75 in the drawing as a switch movement of the type

having a reversible electric motor M which comprises an armature 13 and a field winding 14, but it is contemplated that other types of switch movement, such for example, as the type provided with a pneumatic motor, may be employed if desired.

Remote control of switch mechanism SM is established by means of a control lever E, which may be a switch control lever of an interlocking machine and which is generally positioned at a point remote from the location of switch SM. Lever E preferably is a manually operable circuit controller of the type operable to two extreme positions and biased to an intermediate position. As is readily apparent from an inspection of the drawing, lever E operates as a pole changer to supply line wires 15 and 16 (which extend from the position of lever E to the location of switch S) with current of one polarity or another from a suitable source of current, such as a battery not shown in the drawing but located adjacent the switch control lever and having its two terminals designated by the reference characters B and C. Normally, with lever E in its mid position, the wires 15 and 16 are deenergized.

In accordance with the polarity of current supplied to wires 15 and 16, one or another of two switch operating relays NWR and RWR is adapted to be controlled through the medium of a polarized switch control relay PR mechanically 30 interlocked with a neutral relay NR in such manner that relay PR is permitted to reverse its polar contact only after neutral relay NR is energized and operates its associated armature to its energized position.

Polarized switch control relay PR comprises, as shown, a magnet 17 having two windings 17a and 17b and a polarizing winding 18, which latter winding preferably is provided with a permanently magnetized core 19. Mounted on core 19 is an armature 20, the arrangement being such that when windings 17a-17b are supplied with current of one polarity, armature 20 is operated in a counterclockwise direction to a normal position, that is, the position illustrated in Fig. 1, but that when current of the opposite polarity is applied to windings 17a-17b, the armature is then swung in a clockwise direction to a reverse position. In either event, energization of winding 18 is effected to strengthen the permanent magnetic field and thereby increase the polarizing action of core 19. Armature 20 of relay PR is operatively connected with a polar contact member 21, which is operated to a normal position when armature 20 is in its normal position, to close normal polar contact 20-21. When armature 20 is swung to its reverse position, contact member 21 is swung to a corresponding reverse position and closes reverse polar contact 21-23.

Neutral relay NR controls a pivoted armature 24, the lower end of which projects into the path of movement of a portion of armature 20 of relay PR to prevent movement of the latter armature when relay NR is deenergized. Armature 24 of relay NR carries contact fingers 25a and 25b adapted to close front contacts 26-27 and 28-29, respectively, when relay NR is energized. Contact finger 25a also closes a back contact 30-31 when relay NR is deenergized.

It should be pointed out that the polarized switch control relay usually is positioned adjacent its associated track switch, and hence is subject to relatively severe jars and shocks due to railway traffic moving over or adjacent the switch. It is readily apparent, however, that with 75

5 polarized relay PR mechanically interlocked with neutral relay NR, improper reversal of the polar contacts of the polarized relay cannot be effected by such jars or shocks, thereby protecting against and avoiding improper operation of the switch due to an accidental reversal of the switch control relay contacts.

10 The reference character J designates a switch circuit controller comprising a movable contact member 32 operatively connected with switch S in the usual manner for movement between a normal position (in which it is illustrated) and a reverse position. Contact member 32 of controller J engages a fixed contact member 33 at all positions of switch S except its full normal position, and also engages another fixed contact member 34 at all positions of the switch except when the switch is in its full reverse position.

15 20 The reference character OR designates an overload relay having an overload winding 35 and a stick winding 36. Connected in parallel with overload winding 35 of relay OR is a resistor 37, the function of which will be made clear presently.

25 In describing the operating of the apparatus of Fig. 1, I shall first assume that the apparatus is in its normal condition as illustrated in the drawing. In this normal condition of 30 lever E is in its mid position so that wires 15 and 16 are disconnected from terminals B and C and are, therefore, deenergized, selector SL is in its normal position to condition switch S for motor operation, circuit controlling contact 8-9 35 is closed, relays NR, PR, OR, NWR, RWR and magnet RM are all deenergized, motor M also is deenergized, and switch S and polar relay PR are in corresponding normal positions.

35 40 I shall now assume that switch S is operated by power to its reverse position. To do this, lever E is actuated to its lower position (as viewed in the drawing) to connect wire 15 with the B terminal of the source of current over lever contact 38-40, and to connect wire 16 with the C terminal of the source over lever contact 39-41. Relay NR now becomes energized over an obvious circuit and attracts its armature 24 out of the path of travel of armature 20 of relay PR. The energization of relay NR also closes front contacts 26-27 and 28-29, the closing of 45 the last mentioned contact completing an obvious circuit for winding 18 of relay PR, which circuit is supplied with energy from a local source, such as a battery positioned adjacent the switch. The closing of front contact 26-27 50 of relay NR completes an obvious circuit for reset magnet RM, whereupon its armature 11 is attracted to its energized position and contact 12-12a is closed. This completes a circuit including the source of current located adjacent lever E and the line wires 15 and 16, whereby windings 17a-17b of relay PR are supplied with current of a polarity such that armature 20 of relay PR is operated to its reverse position. It should be noted that a resistor 43a and 55 an asymmetrical unit 44a are connected in parallel with winding 17a and a resistor 43b and an asymmetrical unit 44b are connected in parallel with winding 17b to improve the operation of relay PR.

60 65 70 Lever E may now be released, thereby interrupting the supply of energy to relays NR and PR, and relay NR releases its armature to close back contact 30-31, whereupon reverse operating relay RWR becomes energized over a circuit

75 which may be traced from terminal B through back contact 30-31 of relay NR, circuit controlling contact 8-9, back contact 45-45b of relay OR, reverse polar contact 21-23 of relay PR, the winding of reverse switch operating relay RWR and contact 34-32 of controller J (closed in the normal position of the switch) to terminal C.

80 85 The energization of reverse operating relay RWR causes motor M to become energized over a reverse operating circuit, which extends from terminal B through front contact 46-46a of relay RWR, armature 13 of motor M, front contact 41-41a of relay RWR, field winding 14 of motor M and overload winding 35 of relay OR 15 in parallel with resistor 37, to terminal C. The polarity of energization of motor M is now such that the motor operates switch S to its reverse position, the circuit being maintained (unless motor M becomes overloaded) until the switch reaches its full reverse position, wherein contact 32-34 of controller J is opened. The opening of contact 32-34 of controller J interrupts the previously traced circuit of relay RWR, whereupon the relay releases to terminate operation of 20 motor M and switch S.

25 30 35 40 45 50 55 60 65 70 75 80 85 90 95 Winding 35 of relay OR and resistor 37 are so proportioned that under ordinary operating conditions, the current division between the relay winding and the resistor when motor M is energized is such that the energy level created in relay OR is insufficient to cause the relay to become picked up. However, in the event that motor M becomes overloaded when operating switch S to its reverse position, as might occur if the switch strikes an obstruction or is blocked from moving to its full reverse position, the excessive current drawn by motor M under the latter condition causes resistor 37 to heat up and increase its resistance, thereby increasing the current flow through winding 35 and as a result the energization of winding 35 increases to a point such that the relay picks up to open its back contact 45-45b and close its front contact 45-45a. The opening of back contact 45-45b of relay OR interrupts the previously traced circuit of relay RWR and as a result relay RWR releases to terminate the operation of motor M. The closing of front contact 45-45a of relay OR connects stick winding 36 of relay OR in circuit with back contact 30-31 of relay NR and circuit controlling contact 8-9, and stick winding 36 accordingly becomes energized to hold relay OR picked up until contact 8-9 is opened, or until relay NR becomes energized.

90 95 When the switch is in its full reverse position, or when it is in a mid position and relay OR is held picked up over its stick winding 36, the switch may be restored to its normal position by actuating switch control lever E in its upper direction (as viewed in the drawing). Wire 16 is now connected with the B terminal of the source of current by lever contact 39-42 while wire 15 is connected with the C terminal by lever contact 39-40, and relay NR becomes energized to open back contact 30-31. Thus, in the event that overload relay OR is held energized over its stick winding, the operation of lever E to its upper position and consequent energization of relay NR causes relay OR to release. The energization of relay NR also causes winding 18 of relay PR and reset magnet RM to become energized, with the result that when contact 12-12a of reset magnet RM closes, windings 17a-17b of relay PR are supplied with current of a polarity 75

such as to cause the relay to operate its armature to its normal position. Lever E may now be released, thereby permitting relay NR to become released and close back contact 30-31 to establish a circuit, which includes circuit controlling contact 8-9 and normal polar contact 21-22 of relay PR as well as contact 32-33 of controller J, for normal switch operating relay NWR.

The energization of relay NWR causes motor M to become energized over a normal operating circuit which may be traced from terminal B through front contact 48a-48 of relay NWR, armature 13 of motor M, front contact 49-49a of relay NWR, field winding 14 of motor M, and overload winding 35 of relay OR in parallel with resistor 37, to terminal C. The polarity of energization of motor M is now such that switch S is moved to its normal position. When the switch reaches its full normal position, contact 32-33 of controller J opens to interrupt the circuit of relay NWR whereupon that relay releases to terminate operation of motor M and switch S.

It should be pointed out that in the event motor M is controlled to operate switch S to its normal position and the motor becomes overloaded, relay OR then becomes picked up and establishes the circuit previously traced for its stick winding to hold relay OR energized until relay NR becomes energized due to an operation of lever E to pick up relay NR, or until selector SL is operated to its reverse position to open circuit controlling contact 8-9.

I shall now assume that with the apparatus of Fig. 1 in its normal condition (as illustrated), selector SL is moved to condition the switch for hand operation, thereby opening circuit controlling contact 8-9. Switch S may now be operated to its reverse position by means of hand lever H. If, during an operation of switch S by lever H, lever E is operated in an attempt to remotely control the switch, such remote control is prevented by virtue of contact 8-9 which is held open by selector lever SL. Thus, although a movement of lever E to either of its extreme positions will cause relay NR to become energized and thereby control reset magnet RM to its energized condition, selector lever SL in its reverse position is effective to maintain contact controlling member 7 in its reverse position against the energization of reset magnet RM, and also is effective to prevent the closing of front contact 12-12a of magnet RM. Accordingly, windings 17a-17b of relay PR remain deenergized since the energizing circuit for such windings is open at front contact 12-12a of magnet RM, and as a result relay PR retains its armature in its normal position. Then, if lever E is released to its mid position so that relay NR becomes deenergized and closes back contact 30-31, neither of the two switch operating relays NWR and RWR can become energized, since the circuit for each of the relays is open at circuit controlling contact 8-9. It follows, therefore, that the construction and control of circuit controlling contact 8-9 by selector SL prohibits remote control of the switch during the interval the selector conditions the switch for manual operation. Also, the control of contact 12-12a of magnet RM by selector SL prohibits either relay NWR or RWR from being energized in response to an operation of switch lever E during the interval that selector SL conditions the switch for operation by hand lever H.

In the event that switch S is manually op-

erated to a position out of correspondence with relay PR and the selector is restored to its normal position, the action of contact controlling member 7 in holding circuit controlling contact 8-9 open functions to avoid automatic restoration of the switch to its position of correspondence with polar relay PR. That is to say, when selector SL is restored to its normal position, contact controlling member 7 is held in its reverse position by virtue of the action of its toggle 10, with the result that contact 8-9 is held open. Accordingly, the circuit for normal operating relay NWR which normally would be established with relay NR released and relay PR in its normal position while switch S is in its reverse position, is open at circuit controlling contact 8-9, and consequently automatic restoration of the switch to its position of correspondence with relay PR is avoided.

Relay PR may be restored to control of switch mechanism SM by actuating lever E to either of its extreme positions to cause relay NR to become energized. With relay NR energized, magnet RM also becomes energized to attract its armature 11 to its energized position, thereby closing front contact 12-12a and operating contact controlling member 7 to its normal position to permit circuit controlling contact 8-9 to become closed. With contact 12-12a of reset magnet RM closed due to the energization of that magnet, relay PR will be operated to its normal or its reverse position according as lever E is actuated to its corresponding normal or reverse position to supply wires 15 and 16 with current of normal or reverse polarity. If the position of lever E is such that relay PR is actuated to its position of correspondence with switch S, then when lever E is released and relay NR becomes deenergized, the apparatus will remain in its position wherein switch S and relay PR are in agreement. However, if lever E is actuated to control relay PR to a position out of correspondence with switch S, then when the lever is released and relay NR becomes deenergized, switch S will be controlled to its position of correspondence with relay PR, in a manner pointed out hereinbefore.

From the foregoing description, it can be seen that the apparatus of Fig. 1 permits remote control of the switch by the switch control lever when the selector is positioned to condition the switch for power operation, and that when the selector conditions the switch for manual operation, remote control of the switch by the control lever is prohibited.

It is readily apparent that the control of circuit controlling contact 8-9 is such that if the switch is manually operated to a position out of correspondence with the switch control relay, automatic restoration of the switch to its position of correspondence is avoided when the selector is restored to its position conditioning the switch for power operation. It is also apparent that contact 8-9 is controlled to restore the apparatus for remote control whenever the switch control lever is actuated after the restoration of selector SL to its normal position. It follows, therefore, that apparatus embodying my invention provides a novel and improved switch control system for dual-control switch movements, and requires a minimum of apparatus to at times prohibit power operation of the switch and automatic restoration of the switch to its position of correspondence with the switch control relay.

In Fig. 1, the control line wires 15 and 16 are

normally deenergized since lever E is biased to its mid position where the wires are disconnected from the source of current located at the lever, and the apparatus is arranged to operate during the relatively short interval of time the lever is actuated to connect the source of current to the control wires. Because of the fact that the apparatus of Fig. 1 is caused to operate on a relatively short impulse of current, such apparatus is particularly well adapted for use in systems of the type known as Coded centralized traffic control systems. In such systems, control code impulses are supplied to normally deenergized line wires to effect operation of a switch or other traffic controlling apparatus positioned at a remote point. When the apparatus of Fig. 1 is used in a system of the type mentioned, the control impulse may be supplied by any of the usual and well-known code transmitting devices.

In Fig. 2, a modification of the system shown in Fig. 1 is shown wherein the control line wires are normally connected in an open circuit with the source of current. Lever E¹ of Fig. 2 is of the usual type movable between a normal and a reverse position and remains in its last operated position. The remainder of the apparatus of Fig. 2 is substantially similar to the apparatus of Fig. 1 previously described, except that two additional polar contact members 50 and 51 are controlled by relay PR to form normal polar contacts 50-52 and 51-53 and reverse polar contacts 50-54 and 51-55, which are interposed in energizing circuits shortly to be pointed out for relay NR. Also, overload relay OR¹ of Fig. 2 is provided with a toggle controlled armature 56 which is operated from a normal into an operated position upon energization of overload winding 35 of relay OR¹ by current of overload magnitude, and is retained in its operated position by virtue of the action of its associated toggle 57 until a reset winding 58 provided for relay OR¹ is energized to attract its own armature 59 into engagement with armature 56 to restore the latter armature to its normal position. Armature 56 of winding 35 controls a normally closed contact 60-60a in such manner as to open that contact whenever armature 56 is in its operated position. Armature 59 of winding 58 controls a contact 61-61a to an open or closed position according as winding 58 is deenergized or energized. The parts of the relay are arranged to permit armature 59 of winding 58 to operate into or from its deenergized and energized positions without effecting operation of armature 56 of winding 35, when the latter armature is in its normal position.

Lever E¹ of Fig. 2 in its normal position N connects terminal B with wire 15 and terminal C with wire 16, and in its reverse position, connects terminal B with wire 16 and terminal C with wire 15.

Wires 15 and 16 of Fig. 2, although constantly connected by lever E¹ to the source of current are normally deenergized by virtue of the fact that the circuit across the wires normally is open, the circuit being closed only whenever the lever is moved to a position out of correspondence with the polarized switch control relay, as will be made clear presently.

Assuming, for example, that with the apparatus of Fig. 2 in its normal condition as illustrated in the drawing and in which condition lever E¹, relay PR and switch S are in their respective normal positions, lever E¹ is operated to its reverse position. Relay NR thereupon becomes energized over a circuit extending from terminal B

through contact 38-42 of lever E¹, wire 16, normal polar contact 52-50 of relay PR, normal polar contact 51-53 of relay PR, and the winding of relay NR to terminal C. The energization of relay NR closes front contact 28-29 to energize winding 18 of relay PR, and front contact 26-27 of relay NR also becomes closed to complete a circuit which includes winding 58 of relay OR¹ in series with the winding of magnet RM, thereby energizing reset winding 58 of relay OR¹ (which causes contact 61-61a to close) and reset magnet RM (which causes contact 12-12a to close). In addition, contact 62-63 of relay NR is closed by contact finger 25c of relay NR to complete a circuit for windings 17a-17b of relay PR, which circuit extends from wire 16 through windings 17a-17b of relay PR, contact 12-12a of reset magnet RM, contact 61a-61 of winding 58 of relay OR¹, and contact 63-62 of relay NR to wire 15. The polarity of energization of windings 17a-17b of relay PR is such that the relay operates its armature to its reverse position, thereby opening its normal contacts 52-50 and 51-53 to interrupt the previously traced circuit of relay NR so that relay NR releases. With relay NR released, winding 58 of relay OR¹, reset winding RM, winding 18 of relay PR and windings 17a-17b of relay PR all become deenergized. Also, when back contact 30-31 of relay NR closes, reverse operating relay RWR becomes energized over an easily traced circuit which is similar to the circuit traced for relay RWR of Fig. 1, thereby controlling switch S to its reverse position.

It is to be noted that the reversal of relay PR opens the circuit of relay NR, thereby causing the release of relay NR and opening the circuit for relay PR across the two control wires 15 and 16.

To restore relay PR and switch S to their respective normal positions, lever E¹ is moved to its normal position, thereby energizing relay NR over a circuit extending from terminal B through contact 38-42 of lever E¹, wire 15, reverse polar contact 55-51 of relay PR, reverse polar contact 58-54 of relay PR, and the winding of relay NR to terminal C. With relay NR energized, winding 58 of relay OR¹, reset magnet RM, winding 18 of relay PR and magnet 17 of relay PR are all energized, and the polarity of energization of magnet 17 is now such that armature 29 of relay PR is swung to its normal position, thereby opening its reverse polar contacts 55-51 and 58-54 to interrupt the circuit of relay NR. When relay NR releases and closes back contact 30-31 normal switch operating relay NWR becomes energized to control the switch S to its normal position.

It should be noted that whenever lever E¹ is moved to a position out of correspondence with polar relay PR, the movement of lever E¹ to such position closes a circuit across wires 15 and 16 which energizes relay NR. Relay NR, accordingly, is energized only whenever lever E¹ is moved to a position out of agreement with relay PR.

In the event that switch S is manually operated to a position out of correspondence with switch control relay PR and the selector is restored to its normal position, circuit controlling contact 8-9 is held in its open position by virtue of the toggle biased contact controlling member 7. Thus, when selector SL is restored to its normal position, circuit controlling contact 8-9 being open prevents either relay NWR or RWR from

being energized, and thereby avoids automatic restoration of the switch to its position of correspondence with relay PR after a manual operation of the switch.

5 In the event that circuit controlling contact 8-9 is held open by the toggle biased contact controlling member 7, the contact is restored to its normal position to thereby establish remote control of switch S whenever lever E! is operated 10 to its position out of correspondence with relay PR and relay NR becomes energized. Under the above conditions, the energization of relay NR causes reset magnet RM to become energized and actuate its armature 11 into its attracted 15 position to operate contact controlling member 7 against the action of toggle 10 into its normal position. Circuit controlling contact 8-9 now becomes closed. Thus, for example, if switch S is manually operated to its position out of correspondence with lever E! and relay PR, contact 8-9 becomes closed only when lever E! is moved to its position of correspondence with switch S and causes relay PR to assume its position of correspondence with switch S. In the 20 event that the switch is manually operated and is left at its position of correspondence with lever E! and relay PR when selector SL is restored to its normal position, the operation of lever E! to its position out of correspondence with relay PR 25 causes contact 8-9 to become closed, and also causes relay PR and switch S to be operated to their respective positions of correspondence with lever E!. It follows from the foregoing that remote control of the switch is established only 30 when circuit controlling contact 8-9 is caused to become closed when the switch control lever is moved to a position out of correspondence with the polarized switch control relay.

It should be pointed out that whenever lever 40 E! is moved to a position out of correspondence with relay PR during the interval that selector SL conditions the switch for manual operation, contact 8-9 is held open by selector SL against the energization of reset magnet RM to prohibit 45 remote control at this time. Also, since contact 12-12a of reset magnet RM is held open under the above conditions, relay PR is not operated to its position of correspondence with lever E!, but remains at its position out of correspondence 50 with lever E! until such time as selector SL is restored to its normal position. Then, however, when selector SL is restored to its normal position, contact 12-12a of reset magnet RM closes and relay PR operates to its position of correspondence with lever E!. If, now, switch S is in 55 correspondence with lever E!, no operation of the switch is effected, but if the switch is out of correspondence with lever E!, then relay PR controls the switch operating relays NWR and RWR to cause the operation of switch S to its 60 position of correspondence with lever E!. 70

In the event that overload relay OR! operates its main armature 56 to its operated position due to current of overload magnitude being drawn by motor M, it can be seen that armature 65 56 is restored to its normal position whenever lever E! is moved to its position out of correspondence with relay PR to cause the energization of relay NR and consequent energization of 70 reset magnet 53 of relay OR!. 75

An advantage of the apparatus of Fig. 2 is that automatic restoration of the switch to its position of correspondence with its polarized switch control relay is avoided by means of a 75 circuit controlling contact 8-9, which is so con-

structed and controlled as to require the minimum of apparatus to provide the above protection in switch control systems for a dual-control switch mechanism.

Although I have herein shown and described 5 only two forms of improved switch control systems embodying my invention, it is understood that various changes and modifications may be made therein within the scope of the appended 10 claims without departing from the spirit and scope of my invention.

Having thus described my invention, what I claim is:

1. The combination with a railway track switch having a two-position selector effective in but 15 one position to condition the switch for power operation, of a circuit controlling contact operatively associated with the selector and operated from a normally closed position to an open position when the selector is moved out of its said 20 one position, said contact having means for maintaining the contact in its open position when said selector is restored to its said one position, a switch control lever having normal and reverse extreme positions, power operating means, means 25 controlled by said lever when operated to an extreme position and including said circuit controlling contact in its closed position for controlling said power operating means to move the switch to a position of correspondence with said lever, 30 and means controlled by said lever and effective when and only when said selector is in its said one position for restoring said circuit controlling contact to its normal position upon movement of 35 said lever.

2. The combination with a railway track switch having a two-position selector effective in but one position to condition the switch for power operation, of a circuit controlling contact operatively associated with the selector and operated from a normally closed position to an open position when the selector is moved out of its said one position, said contact having means for maintaining the contact in its open position when said selector is restored to its said one position, a switch control lever having normal and reverse extreme positions, a polarized switch control relay, circuit means controlled by said lever and effective when and only when said selector is in its said one position for operating said relay to a position of correspondence with the extreme position of said lever, power operating means, means controlled by said relay and including said circuit controlling contact in its closed position for controlling said power operating means to operate the switch to a position of correspondence with said relay, and means controlled by said lever and effective when and only when said selector is in its said one position for restoring said circuit controlling contact to its normally closed position upon movement of said lever.

3. The combination with a railway track switch having a two-position selector effective in but one position to condition the switch for power operation, of a circuit controlling contact operatively associated with the selector and operated from a normally closed position to an open position when the selector is moved out of its said one position, said contact having means for maintaining the contact in its open position when said selector is restored to its said one position, a switch control lever having normal and reverse extreme positions and biased to an open intermediate position, a polarized switch control relay, circuit means effective when and only when 70 75

the selector is moved out of its said one position, said contact having means for maintaining the contact in its open position when said selector is restored to its said one position, a switch control lever having normal and reverse positions, a polarized switch control relay, circuit means controlled by said lever and effective when and only when said selector is in its said one position for operating said relay to a position of correspondence with said lever, power operating means for operating the switch, means controlled by said relay and including said circuit controlling contact in its normally closed position for controlling said power operating means to operate the switch to a position of correspondence with said relay, and electromagnetic means controlled by said lever when and only when said lever is out of correspondence with said relay and said selector is in its said one position for restoring said circuit controlling contact to its normally closed position.

9. The combination with a railway track switch having a two-position selector effective in but one position to condition the switch for power operation, of a circuit controlling contact operatively associated with the selector and operated from a normally closed position to an open position when the selector is moved out of its said one position, said contact having means for maintaining the contact in its open position when said selector is restored to its said one position, a switch control lever having normal and reverse positions, a neutral relay, a polarized relay mechanically interlocked with said neutral relay in such manner that said polarized relay can operate its polar contacts only when said neutral relay is energized, means controlled by said lever for energizing said neutral relay when and only when said lever is out of correspondence with said polarized relay, means also controlled by said lever and effective when said neutral relay is energized provided that said selector is in its said one position for causing said polarized relay to operate to a position of correspondence with said lever, power operating means for operating said switch, means controlled by said polarized relay and including said circuit controlling contact in

its normally closed position for controlling said power operating means to operate said switch to a position of correspondence with said polarized relay, and means controlled by said neutral relay and effective when and only when said selector is in its said one position for restoring said circuit controlling contact to its normally closed position. 5

10. The combination with a railway track switch having a two-position selector effective in but one position to condition the switch for power operation, of a circuit controlling contact operatively associated with the selector and operated from a normally closed position to an open position when the selector is moved out of its said one position, said contact having means for maintaining the contact in its open position when said selector is restored to its said one position, a switch control lever having normal and reverse positions, a neutral relay, a polarized relay mechanically interlocked with said neutral relay in such manner that said polarized relay can operate its polar contacts only when said neutral relay is energized, means controlled by said lever for energizing said neutral relay when and only when said lever is out of correspondence with said polarized relay, other means also controlled by said lever and effective when said neutral relay is energized for causing said polarized relay to operate to a position of correspondence with said lever, means controlled by said selector lever in the other of its two positions and interposed in said other means for preventing operation of said polarized relay when said selector is in its said other position, power operating means for operating said switch, means controlled by said polarized relay and including said circuit controlling contact in its normally closed position for controlling said power operating means to operate said switch to a position of correspondence with said polarized relay, and means controlled by said neutral relay and effective when and only when said selector is in its said one position for restoring said circuit controlling contact to its normally closed position. 10 15 20 25 30 35 40 45
